UNITED STATES PATENT OFFICE.

HERBERT T. HERR, OF PITTSBURGH, PENNSYLVANIA, ASSIGNOR, BY MESNE ASSIGNMENTS, TO THE WESTINGHOUSE MACHINE COMPANY, OF EAST PITTSBURGH, PENNSYLVANIA, A CORPORATION OF PENNSYLVANIA.

SPEED-GOVERNOR.

1,205,126.

Specification of Letters Patent.

Patented Nov. 14, 1916.

Application filed March 27, 1913. Serial No. 757,126.

To all whom it may concern:

Be it known that I, HERBERT T. HERR, a citizen of the United States, and a resident of Pittsburgh, in the county of Allegheny 5 and State of Pennsylvania, have made a new and useful Invention in Speed-Governors, of which the following is a specification.

This invention relates to governing device and has for an object to produce a simple, 10 highly sensitive and effective governing device which is capable of controlling the operation of the inlet valve or valve mechanism of an engine or other fluid operated apparatus through the agency of a pressure 15 responsive motor.

A further object is to produce a speed responsive governing device which forms a part of or is included in a fluid circulatory system and controls the delivery of fluid to 20 the system and the pressure of the fluid within the system.

Other objects and advantages as well as the novel details of construction will appear hereinafter, it being understood that changes 25 in proportion and minor details of construction may be resorted to without departing from the spirit of the invention or sacrificing any of its advantages.

The drawing accompanying and forming 30 a part hereof is a sectional view of an embodiment of my invention and discloses a speed responsive device, capable of being driven by the apparatus to be governed, which controls the delivery of fluid from a 35 source of fluid under pressure to a pressure chamber from which fluid is delivered to the motor which controls the operation of the inlet valve or valves of the apparatus to be governed. The arrangement of the governing 40 device is such that the inlet valve or valves of the apparatus to be governed will be opened as the speed of the apparatus decreases in response to an increase in load and will be closed as the apparatus speeds up or 45 exceeds a normal or determined speed.

In the drawings I have illustrated a lay shaft 1 on which is a gear 2 meshing with the gear 3 on the governor spindle. The governor spindle is here illustrated as consisting of two parts, one designated by the 50 reference numeral 4 having rotatable but

not longitudinal movement; the other designated by the numeral 5 having both longitudinal and rotatable movement. The part 4 is connected to the part 5 by links 6 and 6', 55 7 and 7' and the governor weights 8 and 9.

The spindle element 4 is rotatable in bearings 10 and 11, the bearing 11 being connected to a perforate web 12 secured in the governor casing 13. Part of the spindle 60 element 4 is in the form of a housing 14 which constitutes a chamber for a suitable fluid, as for example oil, and communicating with this chamber is a perforate tube 15 exhausting into a chamber 16 communicat- 65 ing with a pipe 17 which may lead to a valve operating mechanism, as for example, an oil relay (not shown). One end of the tube 15 is conical and on the end of the conical portion of the tube is a spring seat 18 oppo- 70 site a similar spring seat 19 between which spring seats, is a coil spring 20. In the upper portion of the element 4 is a bore or channel 21 in which is a ported bush 22. Within the bore 21 and connected to the 75 element 5 is a ported valve 23. This valve has connected to it a conical end 24 which bears upon the spring seat 19.

By reference to the figure it will be observed that the spindle element 5, the valve 80 23 and the removable end 24 are tubular, the end 24 being partitioned from the valve 23 by plug 25. At the upper end of the spindle element 5 are inlet openings 26 which communicate with a suitable source of oil supply 85 through a pipe 27 in which a valve 28 is conventionally shown. Oil may enter the hollow element 5 and pass into the valve 23 and for lubricating purposes a portion of it may pass through the ports 29 into the chan- 90 nels 30 so as to lubricate the bearing 11.

It is to be understood that the throttle valve of a steam engine, particularly for turbines, is normally open so that the hand valve in the steam supply line may be used 95 for starting.

Assuming that the governor is connected up to a turbine when steam is admitted to the turbine and the turbine starts, the lay shaft 1 will start to turn imparting motion 100 through the gear 3 to the governor spindle. The oil admitted through the pipe 27 into

the spindle element 5 will escape through the ports 31 and 32 as soon as the governor weights 8 and 9 move out. The oil will pass into the chamber 33 through chamber 14, 5 pipe 15, chamber 16, through pipe 17 to the oil relay to close the inlet valve a sufficient amount to bring the engine to the proper speed. If the load becomes light, the governor balls 8 and 9 will again fly out and 10 admit more oil through the ports 31, 32 and 33 into chamber 14, pipe 15, chamber 16, and pipe 17 to close the inlet valve still further. Should the load become heavy, the governor weights 8 and 9 will move in to 15 toward the spindle and under the action of the spring 20 the chamber 14 will be placed in communication with the port 34 through the ports 35 and 36 because the hollow end 24 is provided with openings 37; thus oil 20 will be exhausted from the chamber 14 into the casing 13 where it may be returned to the oil system or be drawn off through the outlet 38.

It will be observed that the port 34 exhausts into the casing 13 at a point where the teeth of the gears 2 and 3 mesh so that said gears will be lubricated. For convenience, the lower element 4 of the spindle is made of two parts so that the gear 3 is a 25 split gear which may be held together by the taper-bolts 39 and the nuts 40 whereby the lower element 4 of the spindle may be taken apart for the purpose of inspection and repairs to the spring and its complementary parts. The spindle element 4 is shown as being provided with a gear 41 meshing with a complementary gear 42, these gears 41 and 42 constituting the low pressure oil pump for a lubricating system 30 which does not form a part of this invention.

In accordance with the provisions of the patent statutes, I have described the principle of operation of my invention together 45 with the device which I now consider to represent the best embodiment thereof, but I desire to have it understood that the device shown is only illustrative and that the invention can be carried out in other ways.

50 Having thus described my invention, what I claim is:

1. In a governor, a spindle comprising telescopic parts, one of which is adapted to have rotatable and longitudinal movement 55 imparted to it, and the other of which is adapted to have rotative movement only imparted to it, one of said parts having ports adapted to register with the ports of the other part, and governor weights for causing said ports to register.

60 2. An organized apparatus comprising a liquid circulatory system, a rotatable and longitudinally shiftable hollow spindle included in said system and controlling the 65 delivery of fluid to and the discharge of

fluid from a pressure chamber included in said system, a speed responsive means for controlling the operation of said spindle.

3. A governing device comprising an organized apparatus including a liquid circulatory system having a pressure chamber to which liquid is delivered from a source of supply and from which it is delivered through a delivery port, a spindle for controlling the delivery of liquid to said chamber and the discharge of liquid through a relief port communicating with said chamber, means driven by the apparatus to be governed for rotating said spindle and centrifugally controlled device driven by said spindle for actuating the spindle to control the liquid delivered to the chamber. 75

80 4. A governing device comprising an organized apparatus including a liquid circulatory system having a pressure chamber to which liquid is delivered from a source of supply and from which liquid is discharged through a continually open delivery port and means responsive to the speed of the device to be governed for controlling 85 the delivery of liquid to said chamber and the discharge of liquid through a relief port with which said chamber is provided. 90

95 5. A governing device comprising an organized apparatus including a liquid circulatory system having a pressure chamber to which liquid is delivered from a source of supply and from which it is delivered through a delivery port, and speed responsive means subjected to the pressure within 100 said chamber for controlling the delivery of liquid to said chamber and the discharge of liquid through a relief port with which said chamber is provided.

105 6. A governing device comprising an organized apparatus including a liquid pressure chamber to which liquid is delivered from a source of supply and from which it is delivered through a continually open delivery port, means subjected to the pressure within 110 said chamber for controlling the delivery of liquid to said chamber and the discharge of liquid responsive means for actuating said last mentioned means.

115 7. An organized apparatus comprising a pressure chamber to which liquid is delivered through a rotatable spindle, a port controlled by said spindle through which the liquid is delivered, a relief port controlled by said spindle through which liquid 120 is discharged, centrifugally actuated balls mounted on said spindle for controlling the operation of the spindle, gearing for driving said spindle and a lubricating passage for said gearing communicating with said 125 delivery port.

130 8. A governing device included in a liquid circulatory system, comprising a pressure chamber, to which liquid is delivered from a source of supply and from

which it is discharged and means responsive to the speed of the device to be governed for controlling the delivery of liquid to said chamber and the discharge of liquid from the chamber through a relief port, with which the chamber is connected.

9. A governing device comprising a casing having an inlet, a delivery, and a discharge port, means subjected to the pressure 10 within said casing for controlling communication between the inlet and the delivery ports and between the delivery and the discharge ports, centrifugally actuated means for controlling the operation of said first

mentioned means, and means for rotating 15 said casing and said centrifugally actuated means.

10. In combination with a driving gear and a driven gear intermeshing therewith, centrifugally controlled means for delivering 20 lubricant to said gears.

In testimony whereof I have hereunto subscribed my name this 24th day of March, 1913.
